CORD STRETCHING APPARATUS

Louis M. Cottchett, Hingham, Mass., assignor, by
mesne assignments, to United States Rubber
Company, New York, N. Y., a corporation of
New Jersey

Application September 8, 1938, Serial No. 228,906

4 Claims. (Cl. 28—57)

This invention relates to apparatus for imparting a permanent stretch to cords, such as tire cords, and the invention is directed more particularly to a pair of free-running, grooveless rolls adapted to be operated by the take-up pull exerted upon the cord, to thereby stretch the cord as it passes around these rolls in successive runs.

It has been found that certain improved properties are imparted to a tire cord by permanently stretching, attenuating or elongating the same, since the stretching decreases the size of the cord without correspondingly reducing its strength and has other advantages.

15 It has been proposed heretofore to stretch cords and ropes by passing a number of convolutions thereof around spaced conical grooved rolls so that the successive runs of the cord or rope travel along paths of slightly increased 20 length to effect the desired stretching operation, but in these prior constructions, mechanism was employed for positively driving one or both of the stretching rolls. The driving of such roll or rolls always presented a troublesome problem 25 since their speed of rotation had to be correlated to the speed at which the cord or rope was being wound upon the take-up spool.

The present invention relates to an extremely simple construction which may be quickly and 30 easily threaded up ready to effect the stretching operation and which does not require any power to operate the same other than the take-up pull that is exerted upon the cord being stretched.

35 It is well known that when a thread, cord, rope, or the like is supplied to a rotating drum to be wound thereupon, it will tend to approach the drum in a plane at right angles to the axis of the drum rotation rather than at an angle to such plane. In carrying out the present invention, advantage is taken of this tendency by 40 mounting a pair of stretching rolls so that they will rotate about converging axes, and as a result of this arrangement each run of the cord wound 45 around the stretching rolls approaches the spaced rolls at right angles to their respective axes of rotation. In this manner the successive runs of the cord are kept spaced from each other by their tendency to approach the rolls at right 50 angles to their converging axes.

55 By employing the free-running, grooveless, tapered stretching rolls herein contemplated it is unnecessary to take any special care to space the successive runs of the cord as it is manually wound repeatedly about the rolls, since it is found that as soon as a take-up pull is exerted upon the cord to advance the same about the stretching rolls, the successive runs of the cord will automatically assume a spaced relation to 60 each other, due to the converging arrangement

of the axes about which the rolls rotate. Therefore, all an operator has to do, in starting the cord stretching operation is to wrap the cord around the rolls the specified number of times, and when the operation begins that draws the 5 cord forward about the stretching rolls the cord runs will separate automatically.

A primary feature of the present invention resides in the free-running grooveless stretching rolls which are adapted to be operated by 10 the take-up pull exerted upon the cord being stretched, and in the arrangement of these rolls whereby the successive runs of the cord are spaced automatically from each other and are gradually stretched as they advance from one 15 run to another.

The above and other features of the present invention and novel arrangement of parts will be more fully understood from the following description when read in connection with the accompanying drawing illustrating one good practical form thereof.

In the drawing:

Fig. 1 is a side elevation with parts in section of a pair of cord stretching rolls constructed 25 in accordance with the present invention;

Fig. 2 is a front elevation of the mechanism shown in Fig. 1; and

Fig. 3 is a view similar to Fig. 1 and illustrates the same stretching rolls shown in Fig. 1 30 except that these rolls are spaced about twice as far apart in Fig. 3 as in Fig. 1.

In the embodiment of the invention illustrated in the drawing 10 constitutes a supporting bracket or plate adapted to support the spaced 35 fixed shafts 11 and 12, which shafts rotatably support the free-running tapered stretching rolls 13 and 14. In the construction shown the shaft 11 is rigidly secured to the supporting plate 10 at the desired inclination by drilling or otherwise forming a hole through the plate 10 at nearly a right angle thereto to thereby receive the shank portion of the shaft 11. One face of the plate 10 is cut away at the angle at which this hole is formed to provide a seat for the 40 shoulder 15 formed upon the shaft 11, and the opposite face of the plate 10 is similarly cut away to form a seat for the washer 16. The outer end of the shank of the shaft 11 is threaded as shown to receive the clamping nut 17, whereby 45 this shaft 11 may be firmly clamped in place upon the plate 10 by tightening the nut 17. The shaft 12 may be provided with similar means for firmly securing it in place upon the plate 10 at the desired distance from the shaft 11 and 50 at the desired inclination to this plate.

The stretching rolls 13 and 14 are preferably given the tapered or frustro-conical shape shown and each roll may be provided with the end flanges 18 and 19 shown. These rolls are pref- 55

erably provided with anti-friction bearings, not shown, so that they will run freely upon supporting shafts. Each shaft is preferably provided at its outer end with a grease tip 20.

5 The construction shown in Fig. 3 is exactly the same as that illustrated in Fig. 1, except that the free running rolls 13 and 14 are spaced about twice as far apart in Fig. 3 as they are in Fig. 1. This is done primarily to illustrate that spacing of the rolls farther apart serves to increase the space between the successive runs of the cord being stretched. This also serves to subject a longer length of cord to the stretching operation.

10 15 In each view the cord C is illustrated as passing through a guide eye 21 as it is drawn from some source of supply (not illustrated). This guide eye is provided to direct the cord C about the desired portion of the tapered roll 13.

20 25 It will be noted upon examining either Fig. 1 or Fig. 3 that the cord C passes from the guide 21 to the roll 13 and halfway about this roll in a plane that passes through the guide 21 at right angles to the axis of the shaft 11. It will also be noted that this cord then passes from the point at which it leaves the small end of roll 13, to the roll 14 along a plane disposed at right angles to the axis of the shaft 12 and passing through the cord delivery point upon the roll 13. It will therefore be seen that all of the rear runs of the cord C lying at the far side of the rolls are illustrated in Figs. 1 and 3 as travelling towards the roll 13 along spaced planes disposed at right angles to the axis of the shaft 11, and that all 30 35 of the front runs of this cord travel towards the roll 14 along spaced planes disposed at right angles to the axis of the shaft 12. Since the first mentioned planes are disposed at right angles to the axis of the shaft 11 and the second mentioned planes are disposed at right angles to the axis of the shaft 12, it will be apparent that these two sets of planes are disposed at an angle to each other corresponding to the angle at which the axes of the shafts 11 and 12 converge towards each other. It therefore follows that the distance the wraps are spaced apart about the stretching rolls will be proportional to the angle formed by the axes about which the rolls rotate and also to the distance between the axes at the point under consideration. This is clearly illustrated in Fig. 3 where the roll supporting axes converge towards each other at the same angle as in Fig. 1, but these axes are spaced approximately twice as far apart as in Fig. 1.

50 55 Any desired type of take-up means may be employed to draw the cord C forward from the stretching mechanism of the present invention, and in Fig. 3 a capstan 22 which may be of well known construction, is shown as constituting the means for pulling the cord C forward about the stretching rolls to thereby rotate the rolls 13 and 14 and impart the desired permanent stretch to the cord. The capstan may be supported and driven by the shaft 23.

60 65 It will be understood from the foregoing that no power is required to rotate the rolls 13 and 14 other than that exerted by the take-up means 22 upon the cord C. The cord stretching device of the present invention may be located wherever desired upon a cord winding machine or other cord treating mechanism to impart at such point the desired permanent stretch or elongation to the cord.

70 75 It is here desired to point out that the amount of stretch to be imparted to the cord may be increased or decreased as desired by (1) changing the distance between the axes 11 and 12 to thereby vary the length of the runs being stretched, (2) changing the taper of the rolls 13 and 14 or the inclination of the shafts 11 and 12 to increase or decrease the change in the successive lengths of the runs of the cord being stretched (3) changing the number of windings 10 of the cord about the rolls to thereby increase or decrease the number of runs being stretched.

If it is desired to subject a relatively long length of cord C simultaneously to the stretching operation, then the rolls will be spaced a 15 substantial distance apart as in Fig. 3 rather than close together as in Fig. 1.

Having thus described my invention what I claim and desire to protect by Letters Patent is:

1. In a cord stretching apparatus a pair of 20 free-running, grooveless, tapered rolls rotatably supported in spaced relation to each other to rotate about converging axes and arranged so that the tapered surfaces of each roll converge in the opposite direction to that in which said axes 25 converge and to an amount to stretch the cord, said rolls having the cord to be stretched passed thereabout in spaced runs that travel successively towards the larger ends of the rolls, and means for pulling the leading portion of the 30 cord forward to thereby rotate both rolls and stretch the cord along said runs.

2. In a cord stretching apparatus a pair of 35 free-running, grooveless, tapered rolls rotatably supported in spaced relation to each other to rotate about converging axes and arranged so that the tapered surfaces of each roll converge in the opposite direction to that in which said axes converge, said rolls having the cord to be stretched passed thereabout in successive runs 40 that increase in length as they advance from the smaller toward the larger ends of the rolls, and means for pulling the leading portion of the cord forward to thereby rotate both rolls and stretch the cord in said runs.

3. In a cord stretching apparatus a pair of 45 free-running, grooveless rolls rotatably supported in spaced relation to each other to rotate about converging axes, and at least one of said rolls being tapered to thereby stretch the cord as it 50 travels from the smaller toward the larger end of the tapered roll, said rolls having the cord to be stretched passed thereabout in successive runs that are spaced by the tendency of each run to approach a roll at right angles to its axis of 55 rotation, and means for pulling the leading portion of the cord forward to thereby rotate both rolls and stretch the cord in said runs.

4. In a cord stretching apparatus a pair of 60 free-running, grooveless, tapered rolls rotatably supported in spaced relation to each other to rotate about converging axes and the tapers of 65 said rolls being sufficient to stretch the cord as it travels from the smaller towards the larger ends of these rolls, said rolls having the cord to be stretched passed thereabout in successive runs that are spaced by the tendency of each run to approach a roll at right angles to its axis of rotation, and means for pulling the leading portion 70 of the cord forward to thereby rotate both rolls and stretch the cord in said runs.

LOUIS M. COTCHETT.
